TRANSMISSION SYSTEM

Gabriel M. Giannini, North Hollywood, Calif., assignor, by mesne assignments, to Automatic Electric Laboratories, Inc., a corporation of Delaware

Application November 14, 1941, Serial No. 419,167

10 Claims. (Cl. 179—170)

The present invention relates generally to improvements in signal current transmission systems of the type in which signal controlled switching circuits are provided for partially or completely blocking certain of the signal current channels included therein and, more particularly, to improvements in transmission systems of this character as utilized in intercommunicating systems of the loudspeaking type.

It is an object of the present invention to provide an improved transmission system of the character described, wherein the automatic gain control of the signal transmission channels is accomplished in a simple and reliable manner with a minimum of circuit equipment.

According to another object of the invention, an improved signal responsive gain control circuit is provided which is electronically coupled to an associated signal current channel and utilizes a normally conductive gaseous discharge tube in its operation to control the gain setting of the associated channel.

In accordance with still another object of the invention, an alternating current source is utilized for supplying space current to the discharge tube of the control circuit, whereby a non-conductive condition may instantly be established in the tube by utilizing grid control and without resorting to complicated relay or electronic switching arrangements for accomplishing this purpose.

The invention, both as to its organization and method of operation, together with further objects and advantages thereof, will best be understood by reference to the specification taken in connection with the accompanying drawings in which Figs. 1 and 2 illustrate an improved transmission system constructed and arranged in accordance with the present invention; and Fig. 3 illustrates a modified arrangement of the channel amplifier which may be incorporated in the system shown in Figs. 1 and 2.

Referring now more particularly to Figs. 1 and 2 of the drawings, the transmission system there illustrated is shown as being connected between an east station and a west station of an intercommunicating line. These stations respectively comprise sound translating devices 8 and 9 of the electrodynamic sound powered type, each of which serves both as a transmitting element and a loudspeaking receiver element. The transmission system or repeater network connected between the two sound translating devices 8 and 9 comprises an east-west transmission channel 10 and a west-east transmission channel 11. Each of these channels includes a plural stage amplifier

which functions to increase the signal current amplitude in the direction of signal current transmission therethrough. For the purpose of rendering the east-west channel 10 active and the west-east channel 11 inactive when signal currents are transmitted from the translating device 8 through the channel 10 for reproduction by the translating device 9, a gain control circuit 12 is provided. A similar circuit, indicated generally at 13, is provided for reversely controlling the gains of the two channels 10 and 11 in response to signal current transmission from the translating device 9 through the channel 11 to the translating device 8.

The amplifiers, control circuits and power circuits respectively provided in association with the two channels 10 and 11 are identical in arrangement, and accordingly, like reference numerals, distinguished only by the letters *e* and *w*, have been used to identify corresponding circuit elements. Briefly considered, the amplifier provided in the east-west channel 10 comprises three amplifying stages 14e, 15e and 16e which respectively include the vacuum tubes 17e, 18e and 19e. The input terminals of this amplifier are connected to the terminals of the translating device 8 and the output terminals are connected to the terminals of the translating device 9. More specifically, the first amplifier tube 17e is of the commercial 6J7 pentode type and comprises input electrodes 20e and 21e which are coupled through an input transformer 22e to the terminals of the translating device 8 over a line which may be connected between the east station and the transmission system. The output electrodes 22e and 21e of the tube 17e are coupled to the input electrodes 23e and 24e of the second amplifier tube 18e through a resistance-capacitance coupling network which comprises a coupling resistor 25e and a direct current blocking condenser 26e. The correct operating potential is maintained upon the cathode 21e of the tube 17e through the provision of a cathode biasing network which includes a resistor 31e shunted by a by-pass condenser 32e.

The vacuum tube 18e included in the amplifier of the east-west channel 10 at the second stage thereof is a twin triode of the commercial 6N7 type having its two control electrodes tied together so that the electron streams respectively terminating at the two anodes thereof are controlled in like manners by signal currents impressed between the connected control grids and the cathode 24e. With this arrangement it will be seen that the tube 18e is provided with two

sets of output electrodes. One set of these electrodes, namely, that comprising the cathode 24e and the anode 33e, is coupled to the input electrodes 34e and 35e of the tube 19e through a resistance-capacitance network which comprises a voltage dividing resistor 36e, a coupling condenser 37e, and a direct current blocking condenser 38e. The output electrodes 39e and 35e of the tube 18e are in turn coupled through an output transformer 40e to the terminals of the translating device 9 provided at the west station. For the purpose of maintaining the cathode 35e at the correct operating potential, a cathode biasing network is provided which includes a resistor 41e shunted by a signal current by-pass condenser 42e. A similar network comprising the parallel-connected resistor 43e and condenser 44e is included in the space current path of the tube 18e in order to maintain the proper potential difference between the cathode 24e and the connected control grids 23e.

For the purpose of supplying positive screen and anode potentials to the screen and anode electrodes of the three tubes 17e, 18e and 19e, a full wave rectifier, indicated generally at 45e, is provided. This rectifier comprises a full wave rectifying tube 46e to which alternating current of commercial frequency is delivered through a transformer 47e. More specifically, the transformer 47e is provided with a high voltage secondary winding 48e having a grounded center tap and having its outer terminals connected to the two anodes of the tube 46e. The cathode of this tube is energized from a low voltage secondary winding 49e of the transformer 47e, and is connected to the grounded center tap of the high voltage winding 48e through a filter network which includes the series-connected iron core choke 50e and a pair of shunt connected filter condensers 51e and 52e. The high voltage terminal of the filter network is connected directly to the screen electrode of the amplifier tube 19e and is connected to the anode 39e of this tube through the primary winding of the output transformer 40e. Similarly, the required positive potential is impressed upon the anode 33e of the amplifier tube 18e through a pair of current limiting resistors 53e and 54e, the last of which is by-passed for alternating currents by a condenser 55e. Positive operating potential is also supplied to the anode and screen electrodes of the first amplifier tube 17e through a resistance network which includes the three current limiting resistors 56e, 57e and 58e, the resistors 57e and 58e being by-passed for alternating currents by a condenser 59e.

The control circuit 12 is electronically coupled to the east-west transmission channel 10 and comprises a diode rectifier 60e and a gaseous discharge tube 61e of the commercial 885 type, connected in tandem in the order named. More specifically, the second set of output electrodes 62e and 24e of the second amplifier tube 18e is coupled to the diode 60e through a transformer 63e. The space current path of this diode is connected across the secondary winding of the transformer 63e in series with a small battery 64e and a voltage dividing resistor 65e which is shunted by a smoothing condenser 66e. The bias voltage developed across a portion of the resistor 65e is negatively applied to the control grid 67e of the discharge tube 61e, which tube is connected to operate as a grid controlled rectifier. As indicated above, this tube is of the gas filled type such that current flow therethrough cannot occur

so long as the negative bias on the control electrode 67e exceeds a predetermined value. When, however, the tube becomes ionized the grid 67e loses control, so that the discharge through the tube can only be arrested by reducing the voltage between the output electrodes 68e and 69e substantially to zero. These electrodes are connected in circuit with a biasing resistor 70e which is shunted by a smoothing condenser 71e and is connected through a resistor 72e and the resistor 36e to the control electrode 34e of the tube 19e included in the final amplifier stage 16e of the channel 10. Space current is delivered to the gas-filled discharge tube 61e from an alternating current source of commercial frequency through a voltage transformer 73e. This transformer is provided with a secondary winding 74e which is bridged by a voltage divider 75e, the adjustable portion of which is included in circuit with the biasing resistor 70e and the space current path of the tube 61e. Current for energizing the cathode heater of the tube 61e and the heaters of the vacuum tubes 17e, 18e, 19e and 60e is supplied from a low voltage winding 76e forming a part of the transformer 73e.

In further reference to the arrangement of the control circuit 12, it is noted that this circuit not only controls the bias normally impressed upon the control electrode 34e of the associated channel amplifier tube 19e, but in addition is arranged to control the negative bias voltage impressed upon the control electrode 20w of the amplifier tube 17w. To this end a connection is provided between the voltage dividing resistor 65e and the control electrode 20w which includes a resistor 77w shunted by a by-pass condenser 78w. Similarly, the control circuit 13 is arranged to control both the gain of the final amplifier tube 19w included in the west-east channel 11 and the gain of the first amplifier tube 17e included in the east-west channel 10. To the latter end, the voltage dividing resistor 65w is connected to the control electrode 20e of the tube 17e through a resistor 77e which is shunted by a by-pass condenser 78e.

In considering the operation of the system, it may be assumed that the signal amplifiers provided in the two channels 10 and 11 and the control networks 12 and 13 respectively associated with these amplifiers are conditioned for operation. In this regard it will be noted that when alternating current is delivered to the primary winding of the transformer 47e, current alternately traverses the two anodes of the tube 46e to produce a high direct voltage between the upper terminal of the choke coil 50e and ground. This voltage is positively applied to the screen and anode electrodes of the tubes 17e, 18e and 19e over the paths previously described. With the power transformer 73e energized, current is delivered to the cathode heaters of the tubes 17e, 18e, 19e, 60e and 61e over parallel circuits which may include current limiting resistors, if required. In a similar manner the tubes 17w, 18w, 19w, 60w and 61w included in or associated with the west-east transmission channel 11 are conditioned for operation when current is delivered to the parallel connected primary windings of the two transformers 41w and 73w.

When electron emission starts in the diode 60e, direct current is passed from the battery 64e through the space current path of this tube, the biasing resistor 65e and the secondary winding of the transformer 63e so that a direct voltage is developed across the resistor 65e. This voltage is

negatively applied to the control electrode $61e$ of the gas-filled discharge tube $61e$ over a path which includes the resistor $79e$. The extent of this negative bias is insufficient to prevent current flow through the space current path between the anode $69e$ and the cathode $68e$ of the discharge tube $61e$, but serves to polarize this tube so that when a relatively small increase in the negative bias voltage occurs the tube is rendered non-conductive. In this regard it is noted that the alternating voltage impressed between the two electrodes $68e$ and $69e$ passes through a zero potential value once during each half-cycle thereof, and accordingly when the bias voltage impressed between the two electrodes $61e$ and $68e$ exceeds the space current cut-off value, space current flow through the tube is arrested at the next following zero potential point of the applied voltage. Since the tube $61e$ acts as a grid controlled rectifier, it passes current in only one direction to set up a pulsating current through the biasing resistor $70e$. The resulting voltage appearing across this resistor is smoothed through the action of the condenser $71e$ and is negatively applied to the control electrode $34e$ of the final amplifier tube $19e$ in the east-west channel 10 over a path which includes the resistor $72e$ and a portion of the voltage dividing resistor $36e$. The extent of this voltage is sufficient to bias the amplifier tube $19e$ beyond anode current cut-off so that the east-west channel 10 is normally blocked against signal current transmission.

In a manner similar to that just described with reference to the action of the control circuit 12 , the rectifier $60w$ and the gas-filled discharge tube $61w$, in cooperation with their respective associated circuits, serve normally to provide a direct voltage across the biasing resistor $70w$ which is negatively applied through the resistor $72w$ and a portion of the voltage dividing resistor $36w$ to the control electrode $34w$ of the final amplifier tube $19w$ included in the west-east channel 11 . This voltage serves to bias the tube $19w$ beyond its anode current cut-off point so that the west-east channel 11 is normally blocked against signal current transmission therethrough.

With the system in the condition described above, if a user of the west station speaks into the translating device 9 , a signal voltage is developed across the primary winding of the coupling transformer $22w$. This voltage is reproduced across the secondary winding of the transformer $22w$, is impressed between the input electrodes $20w$ and $21w$ of the first amplifier tube $17w$. When amplified by this tube the signal voltage is impressed through the resistance-capacitance coupling network between the input electrodes $23w$ and $24w$ of the second amplifier tube $18w$. The amplified signal voltage appearing across the output circuit of the tube $18w$ is impressed through the resistance-capacitance coupling network between the input electrodes $34w$ and $35w$ of the final amplifier tube $19w$. Initially, however, the tube $19w$ is blocked against signal current transmission therethrough due to the existing negative bias voltage between the input electrodes thereof.

At the second stage $15w$ of the west-east channel amplifier, the signal voltage as amplified through the tubes $17w$ and $18w$ also appears between the output electrodes $33w$ and $24w$ of the tube $18w$. This voltage is applied across the primary winding of the coupling transformer $63w$, and during alternate half-cycles thereof, additional current is passed by the diode rectifier $60w$

to increase the current flow through the biasing resistor $65w$. The resulting increase in voltage across this resistor is smoothed through the action of the condenser $66w$ and serves to increase the negative bias between the input electrodes $67w$ and $68w$ of the discharge tube $61w$. In response to this increase in bias voltage, the discharge tube $61w$ is rendered non-conductive during the next following zero potential point in the voltage applied across the output electrodes $69w$ and $68w$ thereof. When this tube is rendered non-conductive the voltage across the resistor $70w$ drops to zero to remove the negative bias normally applied to the control grid $34w$ of the final amplifier tube $19w$. This decrease in the bias between the input electrodes of the tube $19w$ serves to render the final amplifier stage $16w$ active, whereby the incoming signal currents are amplified therethrough and are transmitted through the output transformer $40w$ to the translating device 8 for reproduction.

When the signal being transmitted from the translating device 9 through the west-east channel 11 to the translating device 8 is interrupted, the current traversing the space current path of the diode rectifier $60w$ is reduced to its normal value so that the bias voltage impressed between the input electrodes of the discharge tube $61w$ is decreased sufficiently to again permit space current flow through this tube. In this regard it will be noted that the action of the condenser $66w$ prevents an immediate collapse of the bias voltage between the input electrodes of the tube $61w$, and the action of the condenser $71w$ prevents an immediate rise of the bias voltage across the resistor $70w$ to its normal value after space current flow through the tube $71w$ is reestablished. Thus a short period elapses between the interruption of the signal and the increase in the bias voltage across the resistor $70w$ to a value sufficient to block signal current transmission through the tube $19w$. Accordingly, a "hang-over" period is provided which is of sufficient extent to prevent the west-east channel 11 from being rendered inactive or blocked during the spacing intervals between the syllables of ordinary speech. The manner in which the amplifier of the west-east channel 11 and the control circuit 13 operate during further signal transmission from the translating device 9 to the translating device 8 is exactly the same as described above and will be clearly apparent from the preceding explanation.

It will be noted that the signal as amplified through the west-east channel 11 and transmitted to the translating device 8 is also applied to the primary winding of the input transformer $22e$ of the first amplifier stage $14e$ included in the east-west channel 10 . In the absence of some means for blocking the transmission of the signal through the first two stages $14e$ and $15e$ of the east-west channel amplifier 10 , this signal voltage is free to act upon the control circuit 12 in the above described manner to render the final amplifier stage $16e$ operative to pass the signal through the three stages $14e$, $15e$ and $16e$ and the transformer $40e$ to the input transformer $22w'$ of the first amplifier stage $14w$. In other words, a closed circuit is necessarily provided which includes the combined gains of the amplifiers respectively included in the two channels 10 and 11 . With both of these amplifiers active and operating at their normal gain settings, the combined signal current gain therethrough substantially exceeds the losses of the closed circuit, and

hence an unstable condition of the circuit is produced. It is to obviate this difficulty that the control circuit 13 is arranged to block signal transmission through the east-west channel 10 at the first amplifier stage 14e thereof during each interval when the west-east channel is active. To this end the voltage developed across the adjustable portion of the resistor 65w is negatively applied through the resistor 71e and the secondary winding of the input transformer 22e to the control grid 20e of the amplifier tube 17e. Incident to the increase in this voltage which occurs when a signal is impressed upon the primary winding of the input transformer 22w', the first amplifier tube 17e is biased beyond anode current cut-off so that the east-west channel 10 is blocked against signal current transmission therethrough. Obviously this channel is rendered active each time a signal transmitted through the west-east channel 11 is interrupted to cause the voltage across the biasing resistor 65w to be reduced to its normal value.

The manner in which the control circuit 12 functions to render the east-west channel 10 operative to pass signal currents from the sound translating device 3 to the sound translating device 9 during sound wave transmission to the translating device 8, and to block the west-east channel 11 at the first stage 14w, is exactly the same as described above with reference to the operation of the control circuit 13 during signal current transmission in the opposite direction and will be clearly apparent from the explanation pertaining thereto.

Referring now more particularly to Fig. 3 of the drawings, the modified channel amplifier arrangement there illustrated is substantially similar to the amplifier arrangement utilized in each of the two channels 10 and 11 of the system shown in Figs. 1 and 2. Accordingly, corresponding elements of the two amplifier arrangements have been identified in the drawings by the same reference numerals, but the suffix c has been added to the reference numerals in Fig. 3 in order to distinguish the two arrangements. In the arrangement illustrated in Fig. 3 a triode 17c is used at the first amplifier stage 14c, which tube is provided with input electrodes 20c and 21c that are coupled to the secondary winding of the input transformer 22c' through a voltage dividing resistor 80 in order that the proportion of the available signal input may be adjusted to the desired value. At the second stage 15c of the amplifier, a pentagrid mixer tube of the well-known commercial 6L7 type and provided with two control electrodes 23c and 84 is utilized.

In order to substitute the amplifier shown in Fig. 3 of the drawings for the amplifier provided in the west-east channel 11 of the system shown in Fig. 2, the terminals A, B, C, D, E, F, G, and H of the circuit shown in Fig. 3 are connected to the correspondingly labeled terminals shown in Fig. 2. After these connections are made it will be noted that the anode and screen supply voltage as developed through operation of the rectifier 45w is impressed across the voltage dividing resistor 82, and a small portion of this voltage is positively applied to the cathode 24c of the tube 18c in order to maintain the correct potential difference between this cathode and the associated control electrode 23c. Substantially the full voltage appearing across the resistor 82 is also positively applied to the screen electrode of the tube 18c through the resistors 53c and 54c and to the anode 62c of this tube through the

resistors 53c and 85. Suitable by-pass condensers 84' and 86 are provided for preventing audio frequency components of the voltage across the resistor 82 from being impressed upon the anode and screen electrodes of the tube 18c. Current for energizing the cathode heaters of the tubes 17c, 18c and 19c may be supplied from the low voltage winding 16w of the transformer 13w.

In considering the operation of the amplifier as shown in Fig. 3 of the drawings when connected in the manner pointed out above, it will be noted that the voltage normally developed across the resistor 10w of the control circuit 13 is negatively applied to the control electrode 84. The magnitude of this bias voltage is sufficient to prevent the tube 18c from passing signal currents and thus signal current transmission through the amplifier is blocked. With the apparatus in this condition, if a signal voltage is applied to the primary winding of the input transformer 22c', this voltage after amplification through the first amplifier stage 14c is impressed through the condenser 81 upon the primary winding of the transformer 63w. The resulting increase in the bias voltage across the resistor 65w causes the gas-filled discharge tube 61w to be rendered non-conductive and a blocking bias potential to be applied to the first stage of the inactive east-west channel 10, all in the manner previously explained. Incident to the extinction of the space current flow through the tube 61w, the bias voltage as developed across the resistor 10w and negatively applied to the control electrode 84 is reduced substantially to zero, whereby the tube 18c is conditioned to amplify signal currents impressed across the signal input electrodes 23 and 24c thereof. The amplified signal output is, in turn, impressed between the input electrodes of the final tube 19c and transmitted from this tube through the coupling transformer 40c to the translating device 8 for reproduction. When an interruption in the signal voltage applied across the primary winding of the input transformer 22c' occurs, the amplified signal voltage as impressed through the first amplifier stage 14c upon the input transformer 63w of the control circuit 13 is arrested, so that the gas-filled discharge tube 61w is again rendered conductive to restore the high negative bias voltage on the cut-off grid 84 of the second amplifier tube 18c. Incident to the decrease in the voltage across the resistor 65w which occurs when the signal is interrupted, the blocking negative potential applied to the control electrode of the first amplifier stage 14e in the inactive channel 10 is reduced sufficiently to permit signal currents to be passed through this stage and the succeeding amplifier stages to the control circuit 12.

When the opposite channel, i. e., the east-west channel 10, is rendered active to transmit signal currents from the translating device 8 to the translating device 9, the control circuit 12 functions in the manner previously pointed out to impress a relatively high negative bias potential through the resistor 71c and the lower portion of the voltage dividing resistor 80 upon the control electrode 20c of the first amplifier tube 17c. The magnitude of this bias voltage is sufficient to block the first amplifier stage 14c against signal current transmission therethrough, whereby the west-east channel 11 is rendered completely inactive.

While one embodiment of the invention has been described, it will be understood that various

modifications may be made therein without departing from the true spirit and scope of the invention.

What is claimed is:

1. In a transmission system, a signal current channel including a plural stage amplifier, a gaseous discharge tube, a biasing network controlled by said tube and including means for biasing an intermediate or last stage of said amplifier to prevent signal current transmission thereby when said tube is conductive and for reducing the bias on said intermediate or last stage to a predetermined normal value to prevent signal current transmission thereby when said tube is rendered non-conductive, and means coupled to said amplifier at a point preceding said intermediate or last stage for normally maintaining current flow through said tube and for preventing current flow through said tube in response to a signal input to said amplifier.

2. In a transmission system, a signal current channel including a plural stage amplifier, a gaseous discharge tube having a control electrode, a biasing network controlled by said tube and including means for biasing an intermediate or last stage of said amplifier to prevent signal current transmission thereby when said tube is conductive and for reducing the bias on said intermediate or last stage to a predetermined normal value to permit signal current transmission thereby when said tube is rendered non-conductive, a rectifier coupled to said amplifier at a point preceding said intermediate or last stage, a biasing resistor connected to impress a biasing voltage on the control electrode of said discharge tube, and a current source connected to pass current through said resistor and rectifier in series so that the resulting bias voltage which is impressed on said control electrode is normally below the space current cut-off value of said tube thereby permitting current flow therethrough and is increased to a value exceeding the space current cut-off value of said tube thereby preventing current flow therethrough when a signal is impressed on the input side of said amplifier.

3. In a transmission system, a signal current channel including a plural stage amplifier, said amplifier including at one stage thereof a thermionic tube which comprises two sets of output electrodes, one set of said electrodes being included in said signal current channel, a gaseous discharge tube, a biasing network controlled by said discharge tube and including means for biasing a succeeding stage of said amplifier to prevent signal current transmission thereby when said discharge tube is conductive and for reducing the bias on said succeeding stage to a predetermined normal value to prevent signal current transmission thereby when said discharge tube is rendered non-conductive, and means coupled to said other set of output electrodes for normally maintaining said discharge tube conductive and for rendering said discharge tube non-conductive in response to a signal input to said amplifier.

4. In a transmission system, a signal current channel including a plural stage amplifier, said amplifier including at one stage thereof a thermionic tube which comprises two sets of output electrodes, one set of said electrodes being included in said signal current channel, a gaseous discharge tube having a control electrode, a biasing network controlled by said discharge tube and including means for biasing a suc-

ceeding stage of said amplifier to prevent signal current transmission thereby when said discharge tube is conductive and for reducing the bias on said succeeding stage to a predetermined normal value to permit signal current transmission thereby when said discharge tube is rendered non-conductive, a rectifier coupled to the other set of said output electrodes, a biasing resistor connected to impress a biasing voltage on said control electrode, and a current source connected to pass current through said resistor and rectifier in series so that the resulting bias voltage across said resistor is normally below the space current cut-off value of said discharge tube thereby permitting current flow therethrough and is increased to a value exceeding the space current cut-off value of said discharge tube thereby preventing current flow therethrough when a signal voltage appears across said other set of output electrodes.

5. In a transmission system, a pair of channels each including a plural stage amplifier, a gaseous discharge tube individual to one of said amplifiers, a biasing network controlled by said tube and including means for biasing an intermediate or last stage of said one amplifier to prevent signal current transmission thereby when said tube is conductive and for reducing the bias on said intermediate or last stage to a predetermined normal value to permit signal current transmission thereby when said tube is rendered non-conductive, and means coupled to said one amplifier at a point preceding said intermediate or last stage for normally maintaining current flow through said tube and for decreasing the gain of the other channel and preventing current flow through said tube in response to a signal input to said one amplifier.

6. In a transmission system, a pair of channels each including a plural stage amplifier, a gaseous discharge tube individual to one of said amplifiers and having a control electrode, a biasing network controlled by said tube and including means for biasing an intermediate or last stage of said one amplifier to prevent signal current transmission thereby when said tube is conductive and for reducing the bias on said intermediate or last stage to a predetermined normal value to permit signal current transmission thereby when said tube is rendered non-conductive, a rectifier coupled to said one amplifier at a point preceding said intermediate or last stage, a biasing resistor connected to impress a biasing voltage on said control electrode, a current source connected to pass current through said resistor and rectifier in series so that the resulting bias voltage which is impressed on said control electrode is normally below the space current cut-off value of said tube thereby permitting current flow therethrough and is increased to a value exceeding the space current cut-off value of said tube thereby preventing current flow therethrough when a signal is impressed on the input side of said one amplifier, and means for impressing the voltage developed across at least a portion of said resistor on one of the stages of the other amplifier to decrease the gain of said other amplifier when a signal is impressed on the input side of said one amplifier.

7. In a transmission system, a pair of channels each including a plural stage amplifier, one of said amplifiers including at one stage a thermionic tube which comprises two sets of output electrodes, one set of said electrodes being included in the signal current channel through said amplifier, a gaseous discharge tube individual to said one amplifier, a biasing network controlled by said

discharge tube and including means for biasing a succeeding stage of said one amplifier to prevent signal current transmission thereby when said discharge tube is conductive and for reducing the bias on said succeeding stage to a predetermined normal value to permit signal current transmission thereby when said discharge tube is rendered non-conductive, and means coupled to the other set of said output electrodes for normally maintaining current flow through said discharge tube and for decreasing the gain of the other amplifier and preventing current flow through said discharge tube in response to a signal input to said one amplifier.

8. In a transmission system, a pair of channels each including a plural stage amplifier, a gaseous discharge tube individual to one of said amplifiers, a biasing network controlled by said tube and including means for biasing an intermediate or last stage of said one amplifier to prevent signal current transmission thereby when said tube is conductive and for reducing the bias on said intermediate or last stage to a predetermined normal value to permit signal current transmission thereby when said tube is rendered non-conductive, means coupled to said one amplifier at a point preceding said intermediate or last stage for normally maintaining current flow through said tube and for preventing current flow through said tube in response to a signal input to said one amplifier, and means responsive to a signal input to the other amplifier for blocking said one amplifier against signal current transmission at a point preceding said last-mentioned point.

9. In a transmission system, a pair of channels each including a plural stage amplifier, a gaseous discharge tube individual to one of said amplifiers and having a control electrode, a biasing network controlled by said tube and including means for biasing an intermediate or last stage of said one amplifier to prevent signal current transmission thereby when said tube is conductive and for reducing the bias on said intermediate or last stage to a predetermined normal value to permit signal

current transmission thereby when said tube is rendered non-conductive, a rectifier coupled to said one amplifier at a point preceding said intermediate or last stage, a biasing resistor connected to impress a biasing voltage on said control electrode, a current source connected to pass current through said resistor and rectifier in series so that the resulting bias voltage which is impressed on said control electrode is normally below the space current cut-off value of said tube thereby permitting current flow therethrough and is increased to a value exceeding the space current cut-off value of said tube thereby preventing current flow therethrough when a signal is impressed on the input side of said one amplifier, and means responsive to a signal input to the other amplifier for blocking said one amplifier against signal current transmission at a point preceding said last-mentioned point.

10. In a transmission system, a pair of channels each including a plural stage amplifier, one of said amplifiers including at one stage a thermionic tube which comprises two sets of output electrodes, one set of said electrodes being included in the signal current channel through said amplifier, a gaseous discharge tube individual to said one amplifier, a biasing network controlled by said discharge tube and including means for biasing a succeeding stage of said one amplifier to prevent signal current transmission thereby when said discharge tube is conductive and for reducing the bias on said succeeding stage to a predetermined normal value to permit signal current transmission thereby when said discharge tube is rendered non-conductive, means coupled to the other set of said output electrodes for normally maintaining current flow through said discharge tube and for preventing current flow through said discharge tube in response to a signal input to said one amplifier, and means responsive to a signal input to the other channel for blocking said one amplifier against signal current transmission at a point preceding said one stage.
